Fig. 5

FIG. 1 is a perspective view of the illuminated magnifier unit;

FIG. 2 is a bottom view thereof;

FIG. 3 is a front view thereof;

FIG. 4 is an end view from the right side thereof; the left side being the same as the right side;

FIG. 5 is a rear view thereof; these views illustrating the gooseneck flexible character of the lamp by showing the lamps in somewhat different positions.

I claim:

The ornamental design for an illuminated magnifier unit, as shown and described.
